UNITED STATES PATENT OFFICE.

FREDERICK STEINBRENNER, OF BUFFALO, NEW YORK, ASSIGNOR TO
WILHELMINA STEINBRENNER, OF SAME PLACE.

FOLDING CABINET-BEDSTEAD.

SPECIFICATION forming part of Letters Patent No. 256,449, dated April 11, 1882.

Application filed December 22, 1881. (No model.)

To all whom it may concern:

Be it known that I, FREDERICK STEINBRENNER, of the city of Buffalo, in the county of Erie and State of New York, have invented a new and useful Improvement in Folding Beds, 5 of which the following is a specification.

This invention relates more particularly to that class of folding beds in which the bed-frame upon which the mattresses are placed is 10 pivoted to a vertical stationary frame or case in such manner that when the bed is not required for use the bed-frame containing the mattresses can be swung upward on its pivots to a vertical position, in which it rests against 15 the front of the stationary frame, and can be lowered or swung down into a horizontal position when required for use, and in which the weight of the bed-frame containing the mattresses is counterbalanced to a greater or less 20 extent by springs attached to the stationary frame and connected with the rear or shorter end of the pivoted bed-frame by ropes or chains running over suitable guide-pulleys. The springs employed for this purpose in folding beds are generally spiral springs, and are very 25 liable to get out of order or break, thereby causing great inconvenience and sometimes personal injury to the persons using such beds. The object of my invention is to provide a more 30 substantial and reliable counterbalancing contrivance for these folding beds; and it consists of an elliptic spring connected with the stationary frame and the pivoted bed-frame, as hereinafter fully set forth.

35 In the accompanying drawings, Figure 1 is a fragmentary vertical section of a folding bed provided with my improvements. Fig. 2 is a rear elevation thereof. Fig. 3 is a fragmentary elevation; and Fig. 4, a horizontal section, 40 illustrating a modified arrangement of my improved counterbalancing contrivance.

Like letters of reference refer to like parts in the several figures.

A represents the upright stationary frame 45 or case of the folding bed, provided with a head-board, A', and B the rear portion of the bed-frame, provided near its inner or rear end with pivots b, secured to the sides and entering sockets in the stationary case A.

50 C represents the base-piece of the stationary

frame A, upon which the bed-frame B rests near its inner ends when in a horizontal position, the extreme outer end of the bed-frame being supported by legs or props in a well-known manner.

D represents an elliptic spring arranged transversely and in a vertical plane on the rear side of the stationary frame A, and resting at the middle of its lower part upon a horizontal cross-piece, E, secured to said frame. The 55 spring D is secured to the cross-piece E by clips e or other suitable means.

F represents a horizontal cross-piece, which is secured to the upper side of the spring D by clips f or otherwise, and g g represent two 60 ropes, preferably constructed of wire, and attached to the ends of the cross-piece F. These ropes extend from the cross-piece F downward, pass loosely through openings h in the lower cross-piece, E, and run around guide-pulleys i 70 k, attached to the lower portion of the main frame A, and connect with eye-pieces l, secured to both sides of the bed-frame A at the inner or rear end thereof, the eyes being located at the lower inner corners of the bed-frame. 75

The ends of the cross-piece E are provided with angular teeth m, which engage in the spaces between teeth n, formed in vertical plates N, which latter are secured to the posts of the 80 main frame A, and whereby the cross-piece E is firmly secured to the frame A and at the same time rendered vertically adjustable. By raising and lowering the cross-piece E the position of the spring D in the main frame and 85 its tension are adjusted as may be required.

It is obvious that any other equivalent means for adjusting the cross-piece E may be adopted.

O represents vertical guide-bars, which are secured with their upper ends to a stationary 90 cross-piece, P, attached to the frame A and with their lower ends to the adjustable cross-piece E. The lower ends of the guide-bars O are provided with vertical slots, through which pass the fastening-bolts q, whereby the guide-bars O are secured to the cross-piece E. This permits the fastening-bolts q to be raised and lowered with the adjustable cross-piece E. The guide-bars O bear against the outer surfaces of the upper cross-piece, F, and the spring D, and 95 100

the head-board A' bears against the inner sides of said parts, whereby said parts are prevented from twisting or changing their position in a horizontal plane. The ropes g, passing through the openings h in the lower cross-piece, E, also assist in retaining the upper cross-bar, F, and the spring D parallel with the lower cross-bar, E. As the pivoted bed-frame B is swung down from a vertical into a horizontal position the ropes g are drawn in the direction of the arrows, whereby the upper cross-piece, F, is drawn downward and the spring D compressed. The overhanging weight of the bed-frame is to a certain extent balanced by the compression of the spring, and when the bed-frame is raised the reaction of the compressed spring assists in returning the bed-frame to a vertical position. The elliptic spring D is very strong and durable, and renders the movements of the

20 bed-frame easy and noiseless.

If desired, the spring D may be arranged in the base of the stationary frame in a horizontal plane, as illustrated in Figs. 3 and 4; but I prefer the arrangement shown in Figs. 1 and 25 2, because the parts are more accessible when so arranged.

I claim as my invention—

1. The combination, with the case or frame A and the bed-frame B, pivoted thereto, of a

spring, D, an adjustable cross-piece, E, to 30 which the spring is secured, and means, substantially as described, whereby the spring is connected with the bed-frame, substantially as set forth.

2. The combination, with the case or frame A and the bed-frame B, pivoted thereto, of a spring, D, a cross-piece, E, supporting the spring, and having teeth m at its ends, and serrated plates N, secured to the frame A, whereby the cross-piece E can be adjusted, substantially as set forth.

3. The combination, with the frame A, provided with a head-board, A', and pivoted bed-frame B, of a spring, D, cross-pieces E, F, and P, and guide-bars O, whereby the spring and the cross-piece attached thereto are maintained in their proper position, substantially as set forth.

4. The combination, with the frame A, provided with a head-board, A', and pivoted bed-frame B, of the spring D, provided with cross-piece, F, adjustable cross-piece E, cross-piece P, and slotted guide-bars O, substantially as set forth.

FREDK. STEINBRENNER.
